AUTOMOBILE BUMPER

Harold W. Pilkey, Detroit, Mich., assignor to Chrysler Corporation, Highland Park, Mich., a corporation of Delaware

Application July 29, 1957, Serial No. 47,115

Term of patent 7 years

(Cl. D14—6)

FIG. 1

FIG. 2

FIG. 3

FIG. 4

FIG. 5

FIG. 6

Fig. 1 is a top plan view of an automobile bumper, showing my new design;

Fig. 2 is a front elevational view thereof;

Fig. 3 is an end view thereof; and

Figs. 4, 5 and 6 are sectional views taken on the lines 4—4, 5—5 and 6—6 of Fig. 2.

I claim:

The ornamental design for an automobile bumper, substantially as shown.
